MISSILE LAUNCHER

Karol J. Bialy, College Park, Md., assignor to the United States of America as represented by the Secretary of the Navy

Filed May 29, 1959, Ser. No. 816,988
2 Claims. (Cl. 89—1.7)

The present invention relates generally to underground tube launched missiles and more particularly to an improved missile launcher having a device for diverting shock waves from the missile body on ignition of the booster and for increasing thrust on the missile by the booster.

In launching a missile from an underground installed tube, a shock wave develops to the rear of the missile near the bottom of the tube. This shock wave travels at a higher speed than the missile and passes between the missile and the side of the launching tube, thus placing a severe stress on the missile body and causing an inward collapse of the missile covering and damage to the missile fins and wings.

An object of the present invention is to provide a missile launcher for keeping the shock waves developed by the booster gases from affecting or damaging the missile during the launching phase.

An additional object of the invention resides in the provision of means for increasing the thrust on the missile within the launching tube or well during the initial boost phase of missile flight.

Another object of the present invention is to provide a missile launcher incorporating wing tip rollers on the missile cooperating with grooves in the launching tube to increase the launching acceleration of the missile.

Still another object of the present invention is to provide a missile launcher having exhaust means for conveying the initial gases away from the bottom of the launching tube to eliminate any excessive pressure within the launching tube, thus preventing damage to the missile or to the launching tube.

Other objects and many of the attendant advantages of this invention will be readily appreciated as the same becomes better understood by reference to the following detailed description when considered in connection with the accompanying drawings.

FIG. 1 is a vertical sectional view through an underground missile launching installation showing the invention applied to a missile booster;

FIG. 2 is an enlarged detail horizontal sectional view on line 2—2 of FIG. 1; and

FIG. 3 is a detail sectional view of one of the fin tip roller assemblies employed.

The ground launching site of the present invention is constructed as shown in FIG. 1 with a reinforced concrete well or launching tube 12 having a mouth 13, a cylindrical side wall 14 and a base 15 with a conical shaped bottom wall 16. Vertical metallic bars or guideways 17 are embedded in the wall and are provided with metal faces having grooves 18 extending vertically along the surfaces of said bars. Encircling the well 12 within the reinforced concrete wall 14 is a series of relief conduits 19 extending from the base 15 to the ground surface. In the side wall 14 near the bottom wall 16 of the well, slots 20 are formed and connect the bottom of the well with the relief conduits 19. The conical shape or formation of the bottom wall 16 of the well will divert the initial exhaust gases from the booster of a missile against the inner surface 21 of a frusto-conical booster skirt 22 which is mounted on an annular shoulder 23 on the inner surface of the wall 14 near the lower end thereof but above the slots 20. The contour of the bottom wall 16 could have various degrees of inclination depending

2

upon which would provide the greatest increase in thrust to the missile by the deflection of the booster gases.

A guided aero-vehicle or missile 24 having wings 25 and fins 26 is positioned in the tube 12 for launching, as indicated in FIG. 1. A propulsion rocket or booster 27 with fins 28 is attached to the aft end of the missile. As shown in section in FIG. 1, the booster 27 has the usual exit nozzle 29. The missile-booster combination is positioned in the tube 12 with the aft end of the booster resting on the open upward end of the booster skirt 22. The skirt has a central opening 30, and is spaced above the bottom wall 16 of the well so that the booster exhaust gases will travel through the opening and be deflected by the well bottom 16 against the inner surface 21 of said skirt to give additional thrust to the missile.

Each of the wings 25 of the missile and fins 28 of the booster is fitted with a contoured cap 31 which has a plurality of longitudinally aligned bearings 32 for engagement within the grooves 18 of the guideways 17 in the side wall 14. A typical one of the caps 31 is shown in FIG. 3. It is shaped to fit about the outer end portion of, say, one of the fins 28 of the booster, and includes an end wall 33 formed with openings into which the bearings 32 project, and a skirt 34 which embraces the fin. A follower plate 35 is mounted within the cap 31 parallel to the end wall and in contact with the ball bearings 32. A plurality of springs 36 are confined between the plate 35 and the end surface or tip of the fin and serve the two-fold function of retaining the plate 35 and bearings in position and of displacing the cap from the fin after the missile has left the tube.

When the booster is ignited, by means not shown, the missile is launched from the well with the bearings 32 rolling on the guideways 17. The use of bearings reduces the force necessary to launch the missile since there is less friction and inertia than with sliding launching shoes of prior devices. That is, with the same amount of booster power, a greater acceleration of the missile can be accomplished by the use of these bearings. As the missile wings and booster fins emerge from the mouth 13 of the launching tube 12, the caps 31 will be displaced by the springs 36 and will be projected away from the missile. The relief conduits 19 will, as the missile and booster leave the launching tube 12, conduct the products of combustion to the surface of the ground. The conical bottom wall 16 and the skirt 22 are so contoured, and the slots 20 are of such dimensions, that maximum thrust will be obtained from the booster. In practice, it has been found that the total vertical sectional area of the slots 20 is required to be greater than the throat area of the booster nozzle 29 so that the maximum thrust impulses of the booster will not be diminished and that the operation of the booster will not be deleteriously affected.

Obviously many modifications and variations of the present invention are possible in the light of the above teachings. It is therefore to be understood that within the scope of the appended claims the invention may be practiced otherwise than as specifically described.

60 What is claimed is:

1. In a missile launching device comprising a launching tube having longitudinal guideway grooves in the side walls thereof for maintaining alignment of the wings and fins of a missile being launched, a bearing assembly for 65 reducing friction between said wings and fins and said guideway grooves comprising a contoured cap member shaped to fit over the outer end portion of said missile wing or fin, a plurality of longitudinally aligned ball bearings in said cap member, an end wall in said cap member having a plurality of circular apertures therein and through which said bearings project to engage said guideway grooves, the diameter of each of said circular aper-

tures being less than the diameter of its corresponding bearing, a follower plate in said cap member parallel to said end wall and contacting said ball bearings, and a plurality of springs in said cap member confined between said follower plate and the end surface of said missile wing or fin, whereby said bearing assembly reduces kinetic friction between said missile wing or fin and said launching tube and the entire bearing assembly is completely ejected from said missile wing or fin upon exit of said missile from said launching tube.

2. In combination with a missile having wings and fins, a launching tube for receiving said missile in position for launching, said launching tube having bottom and side walls, said bottom wall having a conical formation thereon tapering inwardly of said launching tube to an apex located on the longitudinal axis of said launching tube, a frusto-conically shaped annular skirt member integral with said side wall of said launching tube and spaced above said bottom wall and coaxial with the conical formation of said bottom wall, a plurality of gas pressure relief conduits connecting the bottom of said launching tube with the exterior of said tube, a plurality of longitudinal guideway grooves in the interior side walls of said launching tube for maintaining alignment of said missile wings and fins during launching, a plurality of bearing assemblies, one for each of said wings and fins, each of said bearing assemblies comprising a

5 contoured cap member shaped to fit over the outer end portion of said missile wing or fin, a plurality of longitudinally aligned ball bearings in said cap member, an end wall in said cap member having a plurality of circular apertures therein and through which said bearings project to engage said guideway grooves, the diameter of each of said circular apertures being less than the diameter of its corresponding bearing, a follower plate in said cap member parallel to said end wall and contacting said ball bearings, and a plurality of springs in said cap member confined between said follower plate and the end surface of said missile wing or fin, whereby said entire bearing assembly is completely ejected from said missile wing or fin upon exit of said missile from said launching tube.
